DESIGN FOR A HANDBAG

Alex Glaser, Paris, France, assignor to Richard Alan Inc., a corporation of New Jersey

Application May 28, 1946, Serial No. 130,182

Term of patent 3½ years

(Cl. D87—3)

To all whom it may concern:

Be it known that I, Alex Glaser, a citizen of the Republic of France and a resident of Paris, Seine, France, have invented a new, original, and ornamental Design for a Handbag, of which the following is a specification, reference being had to the accompanying drawings, forming a part thereof.

Figure 1 is a perspective view of a handbag showing my new design, viewed from the front side.

Figure 2 is a side elevation of the opposite side of the handbag,

Figure 3 is a top plan view of the handbag, and,

Figure 4 is a bottom plan view of the handbag.

The cross shading is used to indicate a contrasting color.

The essential features of my design reside in the portions shown in full lines.

I claim:

The ornamental design for a handbag, as shown and described.

ALEX GLASER.
